UNITED STATES PATENT OFFICE

MAURICE W. KANTER, THOMAS L. CLARK, AND WALTER B. WILSON, OF PORT ALLEGANY, PENNSYLVANIA

MOTION-CONTROL MEANS FOR THE SPINDLES OF TEXTILE SPINNING MACHINES

Application filed August 14, 1928, Serial No. 299,618. Renewed May 26, 1930.

The present invention relates to textile spinning machines and has for its principal object to provide means for controlling the spindle for the bobbin so that the bobbin may be renewed, when desired, without interfering with the continuous operation of the machine.

An important object of the invention is to provide a friction drive means for the spindle and a friction brake therefor, both being controlled through the operation of a single control lever and arranged for opposite actuation upon the operation of the lever.

Another important object is to provide a friction disk clutch forming an operative connection between the spindle and a driven shaft and a friction disk brake for the spindle and arranging the clutch and brake for control through a single control lever whereby to reverse the position from the operation of the lever.

Another important object of the invention is to provide a motion control device for spindles of this character permitting a positive drive connection between the driven shaft of each of the spindles and the drive shaft of the spinning machine whereby to prevent the possibility of slippage occurring between said shaft and thus provide for the uniform operation of the spindles of the machine.

An additional object is to provide a motion control device of this character of a simple and practical construction, which is strong and durable, efficient and reliable in performance, which may be installed in operative position upon the spinning machine without necessitating any material changes or alterations in the construction thereof, which is relatively inexpensive to manufacture and install and otherwise well adapted for the purposes for which the same is intended.

Other objects and advantages reside in the special construction, combination and arrangement of the various elements forming the invention as more fully hereinafter described and claimed, reference being had to the accompanying drawings forming part hereof, wherein like numerals refer to like parts throughout, and in which:

Figure 1 is a vertical sectional view

through a spindle mounting embodying the motion control means constituting the subject matter of our invention,

Figure 2 is a transverse sectional view taken substantially along the line 2—2 of Figure 1.

Figure 3 is a side elevational view of the driven shaft for the spindle and

Figure 4 is a fragmentary side elevational view, with parts broken away and shown in section, of the friction clutch providing the drive connection between the driven shaft and the spindle.

Referring to the drawings in detail, where-in for the purpose of illustration we have disclosed a spindle assembly for spinning machines, it being understood that the machine may be provided with any desired number of the spindles, all being operated through a common drive shaft indicated at 5.

At spaced intervals upon the shaft 5, adjacent each of the spindles is arranged a worm wheel 6 operatively engaged with a worm 7 formed on a vertically disposed tubular driven shaft 8. The upper portion of the shaft is formed with a disk or angular plate member 9, cast integrally with the shaft, as may also the worm 7.

The lower end of the shaft is externally threaded as shown at 10 and the entire shaft is closed within a suitable housing 11. The housing is fixedly mounted to a stationary part of the machine 12 by cap screws 13 or the like.

The portion of the housing disposed immediately below the disk 9 is formed with an inturned flange 14 providing a support for a bearing assembly 15 interposed between the flange and the disk 9. The inner portion of the housing adjacent the lower end of the shaft 8 is formed with an inner shoulder 16 providing a seat for a bearing assembly 17 for the lower end of the shaft and secured in adjusted position by a nut 18 threaded on the threaded end 10 of the shaft.

The shaft 8 is thus mounted for rotation within the housing and operated through a direct drive connection by means of the gear and worm 6 and 7 respectively. A spindle 19 is supported on the disk 9 by means of a

collar 20 formed intermediate the ends of the spindle, the portion of the spindle beneath the collar constituting a shank 21 extending through the tubular shaft 8.

5 The lower end of the shank 21 protrudes beneath the lower end of the shaft 8 and is externally threaded as shown at 22. A friction disk 23 is interposed between the disk 9 and collar 20, said disk being constructed of suitable friction gripping material whereby to transmit the rotation motion of the shaft to the spindle when the collar of the spindle is seated upon the disk in engagement therewith.

15 The lower end of the housing 11 terminates in a tubular extension 24 with its lower edge protruding slightly below the lower end of the shaft 8 and disposed for engagement with the lower edge of the extension 24 is a friction disk 25 carried at the lower end 20 of the shank 21 of the spindle by a nut 26 threadedly engaged on the threaded portion 22 of the shank.

25 The nut 26 is secured in longitudinal adjusted position upon the shank by means of a jam nut 27 whereby to secure the disk 25 in adjustable spaced relation with the lower edge of the extension 24 and arranged disengaged therefrom when the collar 20 of the 30 spindle is in engagement with the friction disk 23.

35 Disposed about the lower threaded end of the shank 21 is a coil spring 28 having its upper end abutting the stationary part of the machine 12 and its lower end engaged by a washer 29 freely carried at the lower end of the shank 21.

40 The lower face of the washer 29 is formed with an annular recess in which is seated a bearing assembly 30 retained in position in the under side of the washer by a nut 31 threaded on the lower threaded end of the shank, said nut having its outer surface formed into a head 32 forming a cover for the extreme lower end of the spindle.

45 Disposed for engagement with the head 32 is a bell crank lever 33, which may be attached to the machine for operation in any suitable manner by the operator thereof, as for instance by the foot of the operator whereby to effect an upward movement of the spindle 19 upon the action of said lever.

50 It will be apparent from the foregoing and from a careful inspection of Figure 1 of the drawings, that the spring 28 will normally retain the spindles in a downward position so that the same will be rotated by reason of the engagement of the collar 20 with the friction disk 23 which forms substantially the friction disk clutch for operatively connecting the spindle with the disk 9 of the driven shaft.

55 A positive drive connection is thus provided for the spindle through the gears 6 and 7 for operating the spindle in a manner

well known to the art. Whenever it is desired to throw the spindle out of operation, as for instance, for the purpose of renewing the bobbin, the lever 33 is actuated whereupon the bobbin is moved upwardly through 70 the tubular driven shaft which movement simultaneously effects a disengagement of the collar 20 with the disk 23 and also results in an engagement of the stationary angular extension 24 of the housing with the 75 friction disk 25 to produce a braking action for the spindle.

The spindle may thus be held against movement while the bobbin is changed and without interfering with the continued rotation of the driven shaft 8.

As soon as the lever 33 is released the spring 28 will operate to return the spindle to its downward position whereby to release the brake and permit the engagement of the 85 collar 20 with the disk 23.

It will be appreciated that only a slight vertical movement of the spindle is necessary to throw the same into an out of operative engagement with the driven shaft 8, the extent of such movement to accomplish this result indicated by the dotted lines in Figure 1 of the drawings.

An adjustment for the clutch device is provided by means of the nut 31 for controlling the tension of the spring 28.

It is obvious that our invention is susceptible to various changes and modifications in construction without departing from the spirit of the invention or the scope of the 100 appended claims, and we accordingly claim all such forms of the device to which we are entitled.

Having thus described our invention, what we claim as new is:

1. Motion control means for spindles comprising in combination, a tubular driven shaft having a disk formed at its upper end, a spindle having a collar formed intermediate its ends, and a shank extending below the collar and freely disposed in said shaft with its lower end protruding beneath the shaft, a friction disk interposed between the shaft disk and said collar, a brake for the shank of the spindle, spring means yieldably retaining the friction disk in position with the brake out of braking position and control means for the spindle adapted to slidably actuate the shank whereby to reverse the operative position of the friction disk and plate.

2. Motion control means for spindles comprising in combination, a tubular driven shaft having a head formed at its upper end, a spindle having a collar formed intermediate its ends and a shank extending below the collar and freely disposed in said shaft with its lower end protruding beneath the shaft, a friction disk interposed between the shaft disk and said collar, a brake for the shank

of the spindle, spring means yieldably retaining the friction disk in position with the brake out of braking position, and manual control means for the spindle adapted to vertically actuate the shank whereby to reverse the operative position of said friction disk and said brake.

3. Motion control means for spindles comprising in combination, a tubular shaft having a gear formed thereon providing a gear drive connection for the shaft, a housing provided with a rotatable support for the shaft, a spindle having a collar formed intermediate its ends and a shank below the collar and freely positioned within the shaft with the lower end of the shank protruding below said shaft, an angular member formed at the upper end of said shaft, a friction disk interposed between the collar of the spindle and said angular member, a friction disk adjacent the lower end of the shank, means carried by the shank for adjustably securing said last named friction disk in position for engagement with the lower edge of the housing whereby to constitute a brake for the spindle, spring means arranged at the lower end of the shank and adapted to normally urge the shank downwardly for engagement of said collar with said friction disk, means for adjusting the connection of said spring and a control lever for the spindle engageable with the shank for the vertical actuation thereof whereby to disengage said collar from said first named disk and move said last named disk into braking position with respect to the lower end of said housing.

In testimony whereof we affix our signatures.

MAURICE W. KANTER.
THOMAS L. CLARK.
W. B. WILSON.
